UNITED STATES PATENT OFFICE

CHARLES H. ARNOLD, OF DAYTON, OHIO, ASSIGNOR, BY MESNE ASSIGNMENTS, TO THE NATIONAL CASH REGISTER COMPANY, OF DAYTON, OHIO, A CORPORATION OF MARYLAND

CASH REGISTER

Application filed December 17, 1924. Serial No. 756,532.

This invention relates to cash registers, and more particularly to cash registers of the type described in the patent to Cleal and Reinhard, No. 580,378, issued April 13, 1897, and the patent to Thomas Carroll, No. 703,639, issued July 1, 1902, and the patent to E. J. Von Pein, No. 1,096,973, issued May 19, 1914.

One object of the invention is to provide a single row of keys for differentially controlling an actuating means by depressing one or two keys in this row, the movement of the actuating means being a number of divisions equal to the amount represented by the one key or the combined amounts of two keys.

Another object is to provide a construction whereby a single row of keys depressed in combinations of two will register monetary values of certain denominations ordinarily requiring two rows of keys, such as 20 annas in Indian money, and shillings in English money, as shown in the patent to E. J. Von Pein, No. 1,073,704, issued Sept. 23, 1913.

Another object is to provide means for differentially moving two printing members from a single differential actuating means.

With these and incidental objects in view, the invention consists of certain novel features of construction and combinations of 30 parts, the essential elements of which are set forth in appended claims and a preferred form or embodiment of which is hereinafter described with reference to the drawings which accompany and form part of this specification.

Of said drawings:

Fig. 1 is a transverse section of the machine taken to the left of the key bank with the new mechanism.

Fig. 2 is a detail view of the printing wheel operating mechanism shown in Fig. 1.

Fig. 3 is a detail view of two printing members and their operating connecting mechanism.

Fig. 4 is a detail view of the connecting mechanism shown in Fig. 3.

Fig. 5 is a top plan view of the printing wheel operating mechanism.

Fig. 6 is a detail left side view of the key

bank shown in Fig. 1, with the lower key depressed.

Fig. 7 is a detail left side view of the key bank shown in Fig. 1, with the first and second keys depressed.

Fig. 8 is a diagram of the key arrangement.

Fig. 9 is a perspective view of the differential latch mechanism.

In the drawings the present improvements are shown applied to a machine of the type shown in the patents previously referred to, and to which reference may be had for a general description of the operation and construction of the machine. These patents describe a cash register having a plurality of oscillating segment gears which are controlled differentially in their movements by a plurality of depressible value keys and serve to set indicators, actuate totalizing devices, and set type wheels in the printing mechanism.

The printing mechanism is arranged to print records of transactions on a strip of paper contained in the machine and on receipts which are issued by the machine. As before stated, one of the present improvements is a device for differentially moving two printing members from a single differential actuating means.

The machine shown is adapted for Indian currency, but this is merely by way of illustration, and it may readily be employed for currency of other countries.

The type of machines to which the present improvements are shown applied is old and well known, and only so much of the general structure is shown as is necessary to properly illustrate the improvements. The machine includes a driving shaft and suitable connections (not shown in the drawings) to an oscillating shaft 30 (Fig. 1). The shaft 30 carries a segment 31 for each registering unit which is latched to and unlatched from a segment gear 32 for causing the segment gear 32 to be oscillated different extents upon the operation of the machine, as determined by the particular value keys 33 which are depressed. Each segment gear 32 meshes with an intermediate gear 34, and through this

gear transmits its differential movements to the main or cash totalizer 35. The totalizer, which is of the regular construction for this type of machine, is fully described in the 5 patents previously referred to. The digit wheels of the totalizer are divided into a number of divisions equal to the registering capacity of their respective key banks, as shown in Fig. 8.

During an operation of the machine the 10 segment 31 is moved clockwise to the extent of bringing a shoulder 36 to a position to be engaged by the shoulder 37 formed on the left hand end of a latch 38 supported by two links 39 carried by the segment gear 32. During 15 the return, or counter-clockwise movement, of the segment 31 the segment gear 32 is moved different extents as determined by the particular value of the key depressed. A depressed value key causes the latch 38 to 20 move toward the right a sufficient distance to disengage the shoulder 37 from the shoulder 36 and stop the segment gear while the segment 31 continues its invariable movement.

When the segment gear 32 is not moving with 25 the segment 31 it is held rigid by the right hand end of the latch 38, which is formed to engage a notched bar 40 secured to each frame 41, all of which is old and well known in the art.

30 The usual detent 46 retains a key, when depressed, in such position during the operation of the machine. This detent is latched in operated position by a spring-pulled bar 47, the left hand end of which is bifurcated 35 to engage the shaft 30, and the right hand end of which is guided by a pin 48 mounted on the frame 41, projecting into an elongated opening in the bar. The detent 46 normally engages a shoulder 49 on the bar 47, but, as 40 the detent is moved counter-clockwise by depressing a key, the bar is free to be moved toward the left by its spring 50, placing the top surface 51 of the bar 47 under the detent, where it retains the detent in its operated position to hold a key depressed until a certain 45 time in the operation of the machine when a cam arm 51, secured to the shaft 30, will engage a pin 52 projecting from the bar and move the bar toward the right to normal position to release the depressed key.

50 During an operation of the machine the segment gear 32 is differentially positioned by means hereinbefore described, and is left in that position until during the clockwise movement of the segment 31 during the next 55 operation of the machine, whereupon it is moved clockwise therewith by an arm 53 which engages the segment gear at the point 54. Upon counter-clockwise movement of the 60 segment 31, the segment 32 is again differentially positioned as above described.

Keyboard

65 The keyboard, a diagrammatic view of which is shown in Fig. 8, is arranged for In-

dian currency. The first bank of keys on the right has eleven keys and is used to register 'Pies'; the second bank has eight keys and is used to register 'Annas,' and the remaining banks each have the usual nine keys and is 70 used to register 'Rupees'. The mechanism cooperating with the various key banks, excepting the second from the right having the eight keys, is of the usual construction for a machine of this type, and being old and well known is not shown here, as it is fully illustrated in the patents previously referred to.

75 The key bank having the eight keys is arranged to permit a registering capacity of fifteen keys. This is accomplished by depressing the "1" key together with any one of the other keys in the same bank. Heretofore a registering capacity of this value required fifteen keys arranged in two parallel rows. By this improvement one row of keys is 80 eliminated, which permits a larger total registering capacity for the same size machine.

85 While there are but eight keys in this particular bank, the segment gear 32, or differential mechanism, is adapted to assume a zero and fifteen operated positions controlled by the eight keys. This is accomplished by a pivoted stop 55, carried by a latch support 62 pivoted on the segment gear 32, having two shoulders 56 and 57 (Figs. 6, 7 and 9), one or the other of which engages the end of a depressed key. The stop 55 is controlled by the depression of one or more keys. Said keys 90 control two sliding bars 58 and 59 mounted on pins 60 and 61 supported in the frame 41. When the "1" key is depressed, as shown in Fig. 6, the shoulder 57 engages the end of the key, when the segment gear 32 moves counter-clockwise and causes the pivoted latch support 62 to move clockwise on its pivot 63 and disengage the latch 38 from the segment 31 (Fig. 1). The stop 55 is pivoted at 67 and in zero position is held in contact with a lug 68 by a spring 69. The lug 68 projects from the detent 46, and when the segment gear 32 moves counter-clockwise the stop 55 receives a slight clockwise movement from its spring 69 to position the shoulder 57 so as to engage the end of the depressed key. When a single 100 key of higher value than the "1" key is depressed, the shoulder 56 engages this key to stop the segment gear 32, and an amount equal to the value of the key depressed will be registered.

105 The latch support 62 is bifurcated to engage a pin 70 (Fig. 1) mounted in the latch 38, and through this connection the latch 38 is moved to disconnect the driving segment 31 from the segment gear 32 when the stop 55 110 engages a depressed key.

115 When the "1" key is depressed with another key of higher value, an amount equal to the sum of both keys will be registered. Referring to Fig. 7, which shows the "1" and 120

"2" keys depressed to register "3," the shoulder 57 on the stop 55 engages the end 71 of the "2" key, allowing the segment gear 32 to be moved three divisions of movement. The "1" key being shorter than the other keys, the shoulder 57 clears the end of this key when two keys are depressed, the stop 55 not being permitted to swing on its pivot in a clockwise direction as it does when only one key is depressed.

Referring to Fig. 6, it will be seen that when the segment gear 32 is in its zero position the stop 55 engages the lug 68, which holds the stop in such a position that a spring-actuated pawl 72 can swing under the lower end of the stop, as shown in Figs. 7 and 9, when two keys are depressed. The pawl 72, which is pivoted at 73 to the latch support 62, has a downwardly extending arm 74 contacting an arm 77 of a yoke 75 mounted on a rod 76 supported in the frame 41. Another arm 78 of the yoke 75 contacts a roller 79 carried by a lever 80 pivoted on a stud 81. An upwardly extending arm of the lever 80 carries a roller 82 cooperating with stepped shoulders 88 and 89 of the two sliding bars 58 and 59 (Figs. 6 and 7). When there are no keys depressed in this bank the roller 82 will engage the shoulder 88 on each bar, and if but one key is depressed the roller will engage the shoulder 88 of one bar, as shown in Fig. 6, whereby the pawl 72 is held in such a position that the stop 55 can swing clockwise as the segment gear 32 moves counter-clockwise and the shoulder 57 will engage the end of the "1" key which is depressed. Should any one of the other keys in this bank be depressed instead of the "1" key, the shoulder 56 would engage the end of the key to stop the segment gear 32.

When two keys are depressed in this bank, as shown in Fig. 7, the roller 82 engages the shoulders 89 on both sliding bars 58 and 59 which has permitted a slight counter-clockwise movement of the lever 80, with the result that the pawl 72 has been moved by its spring 90 to the extent of placing the right hand end 91 of the pawl in engagement with the rear side of the lower end of the stop 55. With the pawl 72 in this position the shoulder 57 will not engage the "1" key as the segment gear moves counter-clockwise, but it will engage the other depressed key as it is longer than the "1" key, as previously described.

The sliding bars 58 and 59 are operated by the keys, bar 58 being operated by the "1" key only, through a pin 92 carried by the key and moving in a slot 93 formed in the bar. The other bar 59 is not affected by the "1" key but is operated by all the other keys in this bank by a pin in the keys traversing its appropriate cam slot formed in the bar, as in the bar 58 previously described. The bar 59 is normally retained in home position by a spring 94. The bar 58 does not need a spe-

cial retaining means, as the key pin 92 is always in engagement with the slot 93.

Printer

The segment gear 32, which is differentially positioned under the control of the keys as hereinbefore described, is adapted to differentially adjust two printing members which together are capable of printing numerals from "1" to "15," inclusive.

The segment gear 32 (Figs. 1, 2 and 5) is secured to a hub 100 (Fig. 5) which has fastened on its other end a segment gear 101 meshing with a segment gear 102. The segment gear 102 is mounted on a hub 103 secured to the left hand end of one of a series of telescopic sleeves 104. Fastened to the right hand end of this sleeve is a segment gear 105 meshing with a gear 106 which is secured to the left hand end of one of a series of telescopic sleeves 107 to which is fastened a type wheel 108. This wheel has two groups of digits arranged in the usual way from "0" to "9," inclusive. Cooperating with this wheel to print digits from "10" to "15," inclusive, is a double type segment 109 (Figs. 3 and 5) which has two groups of type characters 116 and 117, each group having a "dot" and the digit "1" with a "dot."

During the time that the type wheel 108 is moved to any position between "0" and "9," the type segment 109 remains in the home position, as shown in Fig. 3, in which position the "dot" will print.

As the type wheel 108 moves past the "9" position to the "0" or tenth position, the type segment 109 automatically moves one position, which places the "1" on this segment in alignment with the "0" on the type wheel 108. Continued movement of the type wheel 108 causes the segment 109 to remain in the moved position so that the numbers from "10" to "15" inclusive may be printed by the combined wheel 108 and segment 109.

The segment 109 is operated by a cam race 110 formed in the side of the type wheel 108. Engaging this cam race is a roller 111 carried on an arm 112 (Figs. 3 and 4) pivoted on a rod 113 supported in the printer frame. Also carried on the arm 112 on the opposite side to the roller 111, is a roller 114 which extends through a slot 115 in the segment 109 to move the segment at the proper time with the type wheel 108.

Operation

A brief description of the operation of the machine will now be given. Referring to Fig. 8, the keys in each of the banks except the anna bank, which is the second bank from the right, are depressed in the usual manner well known in the art. When the number of annas to be registered is equal to one or any even number, a key commensurate with that amount will be depressed in the anna bank.

When the number of annas is uneven, the "one anna key" must be depressed in combination with one of the even number anna keys. This combination of anna keys will control the differential latch in such a way that the differential mechanism (Fig. 1) will be given a movement equal to one step more than that given for the even number key alone. This movement will be transmitted to the totalizer and to the printing wheel so that the amount equal to the amount of the combination of the keys depressed will be entered into the totalizer and printed on the record material. The machine is released and operated in any one of the ways known in the art for machines of this type.

While the forms of mechanism herein shown and described are admirably adapted to fulfill the objects primarily stated, it is to be understood that it is not intended to confine the invention to the forms or embodiment herein disclosed, for they are susceptible of embodiment in various forms, all coming within the scope of the claims which follow.

What is claimed is:

1. The combination of a printing element adapted to be set in a plurality of positions, another printing element in axial alinement with said first printing element adapted to be set in a plurality of positions, and means intermediate the said printing elements for setting one printing element to the same position and holding said one printing element in the said same position, said intermediate means being actuated and held by the other printing element whenever the said other printing element is moved into any one of a plurality of positions.

2. The combination of a plurality of settable printing elements in axial alinement, and means operable upon forward and reverse movement of one of said elements for adjusting the other element to constant predetermined positions.

3. The combination of a pair of settable oscillatable printing elements in axial alinement, and means under control of one element for adjusting the other element to constant predetermined positions.

4. The combination of a settable printing element, another settable printing element, and an arm having two lateral projections, one projecting into a slot in one printing element, the other projecting into a slot in the other printing element for adjusting one of said elements when the other of said elements is in certain positions.

5. The combination of a printing element adapted to be set to a plurality of positions, another printing element in axial alinement with said first printing element adapted to be set in one of two positions, and means intermediate said elements and adjusted by the first-mentioned element for moving the last

mentioned element into either of the two positions, said means adapted to be held in the adjusted position by the first-mentioned element to maintain the second-mentioned element in its adjusted position.

6. In a machine of the class described, the combination of a plurality of keys arranged in a single group, a detent plate adapted to be operated by one of said keys, a second detent plate adapted to be operated by the other keys of said group, said detent plates being arranged to permit the simultaneous depression of the first mentioned key and any one of the other keys, a differential member controlled by all of said keys, a latch device mounted on said differential member, a movable member included in said latch device, a plurality of shoulders on said movable member adapted to engage one of said depressed keys to control the movement of said differential member, means for retaining said shouldered member in either one of two positions to cause a certain shoulder to engage said keys, and means controlled by said detents for controlling said retaining means.

7. In a machine of the class described, the combination of a plurality of keys arranged in a single group, a detent plate adapted to be operated by one of said keys, a second detent plate adapted to be operated by the other keys of said group, said detent plates being arranged to permit the simultaneous depression of the first mentioned key and any one of the other keys, a differential member controlled by all of said keys, a latch device mounted on said differential member, a movable member included in said latch device having a plurality of shoulders adapted to engage one of said depressed keys to control the movement of said differential member, means for retaining said shouldered member in either one of two positions to cause certain shoulders to engage said keys, means controlled by said detents for controlling said retaining means, and a totalizer adapted to be operated by said differential member to have accumulated therein an amount equal to the value of any one key and an amount equal to the value of the sums of a certain key and any other key.

8. In a machine of the class described, the combination of a bank of keys, a differential actuator, a driver therefor, a latch for connecting said actuator to said driver, a member carried by said differential member for moving said latch to disengaging position, a plurality of shoulders on said member singly cooperable with depressed keys, and means controlled by depressed keys for determining which shoulder is to function.

9. In a machine of the class described; the combination of a plurality of keys arranged in a single group; a bar actuated by one of said keys; another bar actuated by any one of the other keys of the group; a differentially movable member; a latch on said member

having two positions of adjustment relative to said member, said latch being controlled by both bars when two keys are depressed, to cooperate with one of said keys to stop the differential member in a position corresponding to the combined amounts represented by the two depressed keys, said latch being also controlled by both bars when any one key of the group is depressed to stop the differential after said differential moves a number of steps equal to the value of the one depressed key.

10. In a machine of the class described, the combination of a plurality of keys arranged in a single group; means actuated by the lowest key in the group; means actuated by any one of the other keys in the group; a differential member; and a latch on said differential member, positioned under control of both of said means when the lowest key is depressed in combination with any of the other keys in the group to place the differential member under control of the depressed key located above the lowest key in the group.

15. 11. In a machine of the class described; the combination of a plurality of keys arranged in a vertical line; means actuated by the lowest key in the vertical line in combination with any other key in the line; a differential member controlled by any one of said keys; and a latch mounted on the differential and positioned under control of said means to stop the differential after the same moves a number of divisions equal to the combined values of the two depressed keys.

20. 12. In a machine of the class described, the combination of a plurality of keys arranged in a vertical line, slidable devices adapted to be operated upon the combined depression of the lowest key with any one of the other keys, a differential member controlled by any one of said keys, a totalizer actuated by said differential member, and means adapted, under control of said devices, to cooperate with the higher key of the two depressed keys to cause said differential member to move a number of divisions equal to the combined values of the two depressed keys.

25. 13. In a machine of the class described, the combination of a plurality of keys arranged in a single group, slidable means operated upon the combined depression of two keys in said group, a differential member controlled by said keys, and a latch device mounted on said differential member and adapted to be controlled by said slidable means to cooperate with one of said depressed keys to allow said differential member to move a number of divisions equal to the sum of the values represented by the two depressed keys.

30. 14. In a machine of the class described, the combination of a totalizer, a plurality of keys arranged in a single group, a slidable member adapted to be operated by the key of lowest value, a second slidable member adapted to

be operated by the other keys of said group, a differential member controlled by all of said keys and adapted to actuate said totalizer, a single stop member carried by said differential member and adapted to engage one of said depressed keys to enable said differential member to actuate said totalizer an amount equal to the combined values of said two depressed keys, and adjustable means controlled by said slidable members to determine which key said stop member shall engage.

35. 15. In a machine of the class described; the combination of a plurality of keys arranged in a single group, the key of lowest value being depressible with any other key in said group; a differential member controlled by all of said keys; and means carried by the differential member to engage the depressed key of highest value to control the differential member.

40. 16. In a machine of the class described, the combination of a totalizer, a plurality of keys arranged in a single group, a slidable member adapted to be operated by one of said keys, a second slidable member adapted to be operated by the other keys of said group and independently of said first mentioned key, a differential member controlled by all of said keys and adapted to actuate said totalizer, a single pivoted stop member carried by said differential member and adapted to engage one of said depressed keys to enable said differential member to actuate said totalizer an amount equal to the combined values of said two depressed keys.

45. 17. In a machine of the class described, the combination of a totalizer, a plurality of amount keys arranged in a single group, means adapted to be operated upon the combined depression of the key of lowest value with another key in said group, a differential member controlled by all of said keys and adapted to actuate said totalizer, a single adjustable stop member carried by said differential member and adapted to be adjusted so as to engage the depressed key of highest value to enable said differential member to actuate said totalizer an amount equal to the combined values of said two depressed keys, and a plurality of pivoted devices controlled by said means to control the adjustment of said adjustable stop member.

50. 18. In a machine of the class described, the combination of a plurality of keys arranged in a single row, the lowest key being depressible in combination with any other higher key in said row; a differential member controlled by the depressed higher key; and means intermediate of said keys and said differential member to stop said differential member after it has moved a number of divisions equal to the combined values of the two depressed keys.

55. 19. In a machine of the class described; the

combination of depressible amount keys; a 5
slidable bar operable by one of said keys; another
slidable bar operable by any one of the
other keys; a differential; a latch carried by
the differential having a shoulder; and mech-
anism intermediate the bars and the latch for
controlling the position of the latch to posi-
tion one of the shoulders in effective relation
with one of the depressed keys.

10 20. In a machine of the class described, the
combination of depressible amount keys; a
slidable member operable by the "1" key; an-
other slideable member operable by any one
of the other keys; a differential member; a
latch on the differential member having two
15 shoulders, the distance between the shoulders
being equal to one step of movement of the
differential member; and mechanism adjust-
ed, when the "1" and one of the higher keys
20 are depressed in combination, to control the
latch to shift one shoulder out of effective
relationship with the "1" key and maintain
the other shoulder in effective relationship
25 with the depressed key of higher value, to
cause the differential to move an extra step
to add one unit more than the value of the
higher key depressed.

21. The combination of a differentially set-
table printing element; a printing element hav-
30 ing a normal and an adjusted position; and
means operable by the differentially settable
printing element upon its forward movement
to move the second mentioned printing ele-
ment to its adjusted position, said means
35 adapted to return the second mentioned ele-
ment to its normal position upon reverse
movement of the differentially settable ele-
ment, said means being held in position by the
settable printing element to maintain the sec-
40 ond-mentioned printing element in its ad-
justed position.

22. The combination of a differentially set-
table printing element; a printing element
having a normal and an adjusted position;
45 a pivoted arm connecting the two printing ele-
ments together to move the second mentioned
printing element to its adjusted position upon
forward movement of the differentially set-
table printing element, and back to its nor-
50 mal position upon reverse movement of the
differentially settable printing element; and
a cam in said first printing element to oper-
ate said pivoted arm.

55 In testimony whereof I affix my signature.
CHARLES H. ARNOLD.
